CLAIM

The ornamental design for a foldably constructed pallet, as shown and described.

DESCRIPTION

FIG. 1 is a top front isometric view of a top blank of a foldably constructed pallet in an unfolded configuration.

FIG. 2 is a top plan view of the top blank of FIG. 1.

FIG. 3 is a bottom plan view of the top blank of FIG. 1.

FIG. 4 is a front elevation view of the top blank of FIG. 1.

FIG. 5 is a rear elevation view of the top blank of FIG. 1.

FIG. 6 is a left side elevation view of the top blank of FIG. 1.

FIG. 7 is a right side elevation view of the top blank of FIG. 1.

FIG. 8 is a top front isometric view of a bottom blank of a foldably constructed pallet.

FIG. 9 is a top plan view of the bottom blank of FIG. 8.

FIG. 10 is a bottom plan view of the bottom blank of FIG. 8.

FIG. 11 is a front elevation view of the bottom blank of FIG. 8.

FIG. 12 is a rear elevation view of the bottom blank of FIG. 8.

FIG. 13 is a left side elevation view of the bottom blank of FIG. 8.

FIG. 14 is a right side elevation view of the bottom blank of FIG. 8.

FIG. 15 is a top front isometric view of a foldably constructed pallet by folding the top blank of FIG. 1 and the bottom blank of FIG. 8 along the fold lines shown by the dotted lines; and,

FIG. 16 is an exploded view of the foldably constructed pallet of FIG. 15.

The top blank and the bottom blank of the foldably constructed pallet are being shown unfolded and separated in some of the figures for ease of illustration.

The dotted lines represent fold lines. The broken lines, which define the bounds of the claimed design, form no part of the claimed design.
